UNITED STATES PATENT OFFICE

ORA L. NEWTON, OF KANSAS CITY, MISSOURI

GARMENT STRETCHER

Application filed October 3, 1929. Serial No. 397,074.

My invention relates to improvements in garment stretchers.

It is particularly well adapted for the stretching of dresses or trouser legs.

One of the objects of my invention is to provide a novel stretcher of the kind described, which is simple, cheap, strong, durable, not likely to get out of order, which is easily and quickly operated, and which is efficient in its operation.

The novel features of my invention are hereinafter fully described and claimed.

In the accompanying drawings, which illustrates the preferred embodiment of my invention,

Fig. 1 is a plan view of my improved stretcher.

Fig. 2 is an enlarged end view thereof.

Fig. 3 is an enlarged section on the line 3—3 of Fig. 2.

Fig. 4 is a reduced plan view showing my improved stretcher applied to a dress.

Fig. 5 is a reduced plan view showing my improved stretcher applied to a trouser leg.

Similar reference characters designate similar parts in the different views.

1 and 2 designate respectively two members, preferably bars square in cross section, which are hinged together at one set of ends by means of a pin 3, or other suitable means. As shown the member 1 has a tenon 4 fitted to swing in a mortise 5 in the adjacent end of the member 2.

Two handles are respectively slidably mounted on the members 1 and 2, so as to be adjustable toward and from each other. Said handles comprise each a head 6 and a stem 10.

The head 6 is provided therethrough with a square hole 8 adapted to receive therethrough one of the members 1 or 2. It is also provided with a transverse threaded hole 9 in which is adjustably fitted the threaded end of a stem 10.

The handles have the heads 6 thereof fitted on the members 1 and 2 with the stems of the handles extending from the same side of the members 1 and 2 and in a plane at right angles to the axis of said members. Each of the members 1 and 2 forms a support on which one of said handles is adjustable to-

ward and from the other handle, and each of said members 1 and 2 also forms a pivotal connection for one of said handles with the other of said members, whereby said handles may be swung toward and from each other.

The stems 10 of the handles are adapted to be respectively screwed in the holes 9 so as to respectively bear against the members 1 and 2 to releasably hold the heads 6 in the positions to which they may be adjusted on the members 1 and 2, Fig. 2.

The stems 10 of the handles are adapted to be inserted into a dress or into a trouser leg and then swung apart so as to stretch the dress or trouser leg.

When a dress is to be stretched, the stems are inserted therethrough, the shoulders of the dress 11 being respectively mounted on the members 1 and 2, as shown in Fig. 4.

The heads 6 are adjusted on the members 1 and 2 to the proper distance apart to suit the width of the dress at its upper end. The stems 10 are then screwed tightly against the members 1 and 2 adjacent thereto, thus holding the heads firmly clamped in their adjusted positions.

The dress, so mounted with the stems spread apart, as shown in Fig. 4 and in dotted lines in Fig. 1, is held over a steam table to moisten the dress, after which it is withdrawn and permitted to dry in the stretched condition while being held stretched by the stems 10.

When stretching a trouser leg, the stems are inserted through the leg 12 of the trousers, Fig. 5, the heads 6 being adjusted to suit the width of the trouser leg.

The stems 10 are then tightened against the members 1 and 2 respectively, after which the trouser leg, held stretched by swinging the stems 10 apart, is held over a steam table to moisten the material of the leg, and then, like the dress, the leg so held is withdrawn from over the steam table and permitted to dry while held by the stems in the stretched condition. By drawing lengthwise the dress 11 or trouser leg 12 with the hands holding the stems 10, the dress or trouser leg may be stretched lengthwise to the proper length, following which the stems 10 are

swung apart to stretch the garment to the desired width, thereby obtaining proper length and width in one operation. While thus held stretched the garment is moistened and then dried, as has been described.

5 As shown in Figs. 2 and 3, the heads 6 may each have inserted through it at opposite sides respectively of the hole 8, re-enforcing bolts 13 provided respectively with nuts 14, for preventing splitting of the head.

10 The threaded hole 9 in each head 6 intersects the square hole 8 and may be threaded its entire length, so that, in case the threads in the block or head 6 becomes worn or broken, the head may be reversed and the stem 10 fitted in the other end of the threaded hole 9.

15 The pin 3 is, preferably, removable, to enable the ready insertion of the members 1 and 2 into dresses with narrow skirts. In such a case, after the members 1 and 2 have been inserted, the pin 3 is replaced into its operative position hingedly connecting the members with each other. Or other suitable 20 means for hinging the members 1 and 2 may be employed.

25 I do not limit my invention to the structure shown and described, as modifications, within the scope of the appended claims, may 30 be made without departing from the spirit of my invention.

What I claim is:—

1. In a garment stretcher, two members 35 hinged to each other, and two handles respectively adjustable toward and from each other on said members and extending therefrom in a plane at an angle to the axis of said members, and adapted for insertion into a dress or trouser leg and to be swung apart 40 to stretch said dress or trouser leg, each handle having means for being releasably clamped to its supporting member in the position thereon to which it may be adjusted.

2. In a garment stretcher, two members 45 hinged to each other, and two handles each comprising a head, said heads being respectively slideable on said members, each of said heads having a threaded hole registering with the adjacent member, and two stems having 50 one set of ends threaded and fitted respectively in said threaded holes and adapted to bear respectively against said members to hold said heads from movement thereon and extending in a plane at an angle to the axis 55 of said members, and adapted for insertion into a dress or trouser leg and to be swung apart to stretch said dress or trouser leg.

3. In a garment stretcher, a support, two handles adapted for insertion into a dress 60 or a trouser leg, one of said handles being adjustable on and lengthwise of said support and having releasable means for being clamped to said support in the position thereon to which it is adjusted, and means pivotal- 65 ly connecting the other of said handles to

said support, whereby said handles may be swung apart to stretch said dress or trouser leg.

4. In a garment stretcher, a support, two handles adapted for insertion into a dress or trouser leg, one of said handles being pivoted to said support, the other handle comprising a head adjustable lengthwise of and on said support and having a threaded hole registering with said support and a stem having a threaded end fitted in said hole and adapted to bear against said support.

15 In testimony whereof I have signed my name to this specification.
